UNITED STATES PATENT OFFICE.

WILLIAM WHALEY, OF KNOXVILLE, TENNESSEE.

RAILWAY ART.

Application filed May 25, 1922. Serial No. 563,506.

To all whom it may concern:

Be it known that I, WILLIAM WHALEY, a citizen of the United States, residing at Knoxville, in the county of Knox and State 5 of Tennessee, have invented a new and useful Improvement in Railway Art, of which the following is a specification, reference being had to the accompanying drawing.

This invention relates particularly to 10 railroad tracks leading to places where cars are to be loaded or work is being performed by a loading or excavating or cutting machine or other apparatus supported on the track, the track requiring forward extension 15 or advancing as the work progresses and space is cleared at the forward end of the track for the support of the extension of the track.

The object of the invention is to provide 20 a method and means for making an endwise extension of such a track by laying temporary or extension track rails beside permanent rails and letting the temporary rails project beyond the ends of the permanent 25 rails as far as clear ground surface at the time permits, then temporarily securing the extension rails, and afterward releasing the temporary rails and moving them forward as far as clear ground surface then permits, 30 and then again securing said temporary rails, these steps being repeated until the rear ends of the temporary rails clear the ends of the permanently set rails, and then placing the temporary rails into permanent 35 position and securing them in permanent manner.

In the accompanying drawings:

Fig. 1 is a plan of a railway track embodying my improvement;

40 Fig. 2 is a cross section through two overlapping rails in Fig. 1;

Fig. 3 is a horizontal section on the line, 3-3, of Fig. 2;

45 Fig. 4 is an elevation of the structure shown in Fig. 2, looking toward the left;

Fig. 5 is a modification of the structure shown by Figs. 2 and 3, a set bolt being substituted for a wedge;

50 Fig. 6 is a side elevation showing one of the extension rails and a chair supporting said rail;

Fig. 7 is an upright section on the line, 7-7, of Fig. 6, looking toward the left;

Fig. 8 is a horizontal section on the line, 8-8, of Fig. 7;

Fig. 9 shows a chair applied to a metal cross tie.

Referring to said drawings, T, T, are track ties of any ordinary form. A, A are track rails of ordinary form each having a 60 foot, A¹, a web, A², and a head, A³. These rails are set on the ties in the usual manner, the foot of each rail resting flatwise on the ties and secured thereto, as by ordinary spikes, S, driven into the ties and engaging 65 the foot of the rail.

B, B, are two extension rails. These are like the rails, A, A, in size and shape of cross-section; but they are inverted and over-lap and are temporarily secured to the 70 rails, A, A, while the forward ends of the rails, B, B, rest in chairs which rest on ties, T, and have the form shown by the drawings.

Each inverted rail, B, has its head, B³, 75 resting on the adjacent foot, A¹, of the rail, A, and against the adjacent web, A², of the rail, A. And the web, B², of the rail, B, rests sidewise against the head, A³, of the rail, A, and the foot, B¹, rests on the head, 80 A³, of the rail, A. Or I may say that the head of each rail rests against the web and foot of the adjacent rail.

A clamp, C, has a horizontal part, C¹, extending under and against the foot, A¹, of 85 the rail, A. From said horizontal part an upright part, C², extends upward nearly to the foot, B¹, of the rail, B, and far enough from the web, B², to allow the insertion of a wedge, W, between the part, C², and said 90 web. At the opposite side of the rail, A, the clamp, C, has a part, C³, which extends obliquely upward until it bears against the adjacent face of the web, A², of the rail, A. Driving the wedge, W, parallel to the length 95 of the rails, will cause the part, C³, to bear with greater force against the web, A², and will cause greater pressure by the wedge against the web, B². Thus the head of each rail is forcibly pressed against the web of 100 the adjacent rail. This results in so securing the extension rails, B, to the permanent rails, A, as to adapt the inverted foot of the extension rail to support track wheels, G, of 105 a car or working structure movable on the track.

Forward of the forward ends of the permanent rails, A, chairs, D, are placed between the ties, T, and the extension rails, B, for supporting said rails. Each such chair has a flat base, D¹, with marginal notches, D², for receiving spikes, S, which are driven into the ties, T, at as many of the chairs, D, as is deemed desirable for holding said rails until such time as they are to be placed into permanent position. Each chair has two upright members, D³, which are parallel to the length of the track and separated a little more than the horizontal thickness of the head, B³, and less than the width of the foot, 10 B¹. Thus said members, D³, form a channel within which the head, B³, of the rail, B, may rest while the inverted foot, B¹, of said rail is seated on the upper edges of said members. At the outer side of each member, 20 D³, is a web, D⁴, formed integral with said member and the outer part of the base, D¹. In each member, D³, of the chair is a horizontal bolt hole, D⁵, placed at the proper height to allow a bolt, D⁶, to extend through 25 said holes and the ordinary splice bar hole, B⁴, near the forward end of the rail, B. Thus only the forward ends of the extension rails are bolted. The rails are not secured to the other chairs; but those chairs are also 30 spiked to the ties to such extent as may be desired.

When more track supporting space has been formed at the front of the track, one or more additional ties are laid and chairs 35 placed thereon, and the temporary rails, B, are released and moved forward and again clamped to the forward permanent rails and seated in the chairs. This is repeated until the rear ends of the rails, B, no longer overlap 40 the forward permanent rails. Then the rails, B, are turned into right position, and placed end-to-end against the permanent rails, the foot of each temporary rail now coming flatwise on the ties. Then those rails 45 are permanently secured to the ties, and they are now the forward permanent rails. As the work progresses and additional track supporting space has been provided, another pair of rails are inverted and brought into 50 over-lapping position with the now forward permanent rails and supported on ties and chairs.

In Fig. 5, the wedge, W, is omitted, and a set bolt, C⁴, is threaded through the upper right part, C², of the clamp and made to bear against the rail web, B².

In Fig. 9, a metal cross tie, U, is substituted for the wooden tie shown by the other figures. The tie, U, has bolt holes, U¹, which receive bolts, S¹, in place of the spikes, S. A washer, S², surrounds each bolt above the base, D¹.

I claim as my invention:

1. The herein described method of building a railway track, which method consists

in laying ties and placing thereon rails having a foot and a web and a head and securing said rails on said ties in permanent form with the foot resting on the ties, and then over-lapping the end of each forward permanent rail with a like rail inverted, the head of each rail being brought into engagement with the web and foot of the adjacent rail, temporarily clamping said rails to each other, and supporting the parts of said inverted rails which are forward of said permanent rails and thereafter releasing the inverted rails and placing them end-to-end against the forward permanent rails and turning them into right position and securing them in permanent manner, substantially as described. 70 75 80

2. The herein described method of building a railway track, which method consists in laying ties and placing thereon rails having a foot and a web and a head and securing said rails on said ties in permanent form with the foot resting on the ties, and then over-lapping the end of each forward permanent rail with a like rail inverted, the head of each rail being brought into engagement with the web and foot of the adjacent rail, temporarily clamping said rails to each other, and supporting the foot of each of said inverted rails forward of the permanent 90 rails and thereafter releasing the inverted rails and placing them end-to-end against the forward permanent rails and turning them into right position and securing them in permanent manner, substantially as described. 95 100

3. The herein described method of building a railway track, which method consists in laying ties and placing thereon rails having a foot and a web and a head and securing said rails on said ties in permanent form with the foot resting on the ties, and then over-lapping the end of each forward permanent rail with a like rail inverted, the head of each rail being brought into engagement with the web and foot of the adjacent rail, temporarily clamping said rails to each other, and supporting the parts of said inverted rails which are forward of said permanent rails and thereafter progressively 105 releasing the inverted rails from the forward rails and moving the inverted rails forward and resecuring and supporting them, until the inverted rails no longer overlap the forward permanent rails, and then turning said inverted rails into right position and placing them end-to-end against the forward ends of the forward permanent rails, and then securing the last-placed rails to the ties in permanent manner, substantially as described. 110 115 120

4. The herein described method of building a railway track, which method consists in laying ties and placing thereon rails having a foot and a web and a head and securing 125 130

ing said rails on said ties in permanent form with the foot resting on the ties, and then over-lapping the end of each forward permanent rail with a like rail inverted, the 5 head of each rail being brought into engagement with the web and foot of the adjacent rail temporarily clamping said rails to each other, and supporting the foot of each of said inverted rails forward of the 10 permanent rails and thereafter progressively releasing the inverted rails from the forward rails and moving the inverted rails forward and resecuring and supporting them, until the inverted rails no longer over- 15 lap the forward permanent rails, and then turning said inverted rails into right position and placing them end-to-end against the forward ends of the forward permanent rails, and then securing the last-placed rails 20 to the ties in permanent manner, substantially as described.

5. In the railway art, the combination of ties, permanent rails seated on said ties and having a foot and a web and a head, a pair 25 of extension rails having the same cross section as the permanent rails and being inverted and over-lapping the forward permanent rails, the head of each over-lapping rail bearing against the foot and web of the 30 adjacent rail, means for clamping the over-lapping parts of said rails to each other, and chairs for receiving and supporting the forward parts of the inverted extension rails, substantially as described.

35 6. In the railway art, the combination of ties, permanent rails seated on said ties and having a foot and a web and a head, a pair of extension rails having the same cross section as the permanent rails and being inverted and over-lapping the forward permanent rails, the head of each over-lapping rail bearing against the foot and web of the 40 adjacent rail, means for clamping the over-lapping parts of said rails to each other, and chairs for receiving and supporting the forward parts of the inverted extension rails, and means for securing said rails to said 45 chairs, substantially as described.

7. In the railway art, the combination of 50 ties, permanent rails seated on said ties and having a foot and a web and a head, a pair of extension rails having the same cross section as the permanent rails and being inverted and over-lapping the forward permanent rails, the head of each over-lapping rail bearing against the foot and web of the 55 adjacent rail, means for clamping the over-lapping parts of said rails to each other, and chairs having supports for the foot of the 60 the inverted extension rails and having a space to receive the head of the inverted rails, substantially as described.

8. In the railway art, the combination of 65 ties, permanent rails seated on said ties and having a foot and a web and a head, a pair

of extension rails having the same cross section as the permanent rails and being inverted and over-lapping the forward permanent rails, the head of each over-lapping rail bearing against the foot and web of the adjacent rail, means for clamping the over-lapping parts of said rails to each other, 70 chairs having supports for the foot of the inverted extension rails and having a space to receive the head of the inverted rails, and 75 means for securing the rails to the chairs, substantially as described.

9. In the railway art, the combination of ties, permanent rails seated on said ties and having a foot and a web and a head, a pair 80 of extension rails having the same cross section as the permanent rails and being inverted and over-lapping the forward permanent rails, the head of each over-lapping rail bearing against the foot and web of the 85 adjacent rail, means for clamping the over-lapping parts of said rails to each other, chairs having supports for the foot of the inverted extension rails and having a space to receive the head of the inverted rails, and 90 bolts extending horizontally through said chairs and said rails, substantially as described.

10. In the railway art, the combination of ties, permanent rails seated on said ties and 95 having a foot and a web and a head, a pair of extension rails having the same cross section as the permanent rails and being inverted and over-lapping the forward permanent rails, the head of each over-lapping 100 rail bearing against the foot and web of the adjacent rail, clamping means including a wedge for securing the over-lapping parts of said rails to each other, and chairs for supporting the forward parts of the extension rails, substantially as described.

11. In the railway art, a chair having upright members separated to receive between them the head and web of an inverted rail while the foot of said rail extends across 110 said members, substantially as described.

12. In the railway art, a unitary chair having a base and two upright members adapted to form seats for the foot of an inverted rail and said members being separated to form a space to receive the head of 115 said inverted rail, substantially as described.

13. In the railway art, a unitary chair having a base and two upright members 120 adapted to form seats for the foot of an inverted rail and said members being separated to form a space to receive the head of said inverted rail, and a bolt extending horizontally through said members, substantially 125 as described.

14. In the railway art, a unitary chair having a base with side notches and having upright members separated to receive between them the head and web of an inverted 130

rail while the foot of said rail extends across and is seated on said members, substantially as described.

15. In the railway art, a chair having a base with side notches and having two upright members adapted to support the foot of an inverted rail and said members being

separated to form a space wide enough from top to bottom to receive the head of said inverted rail, substantially as described.

In testimony whereof I have signed my name, this 8th day of May, in the year one thousand nine hundred and twenty-two.

WILLIAM WHALEY.
